UNITED STATES PATENT OFFICE

EDWIN R. BEEMAN, OF MINNEAPOLIS, MINNESOTA

ELECTRICAL DOOR OPERATING DEVICE

Application filed May 14, 1928. Serial No. 277,728.

My invention relates to electrical door operating devices, and an object of the invention is to provide a device of this character by means of which doors of buildings such as garages may be opened and closed upon the operation of a manually operable switch which may be located in any desired position as for instance in the house occupied by the user of the garage. A particular object is to provide a device embodying an electric motor in combination with a manually operable switch and an automatically operated switch device, the arrangement being such that when the manual switch is placed in one position with the automatic switch device in a corresponding position, the doors will be moved toward open position, and when they reach such position, the automatic switch device will be moved not only to cut off current from the motor but will be set in such position that current will be caused to pass through the motor to operate it in reverse direction when the manual switch is placed in another position thereby closing the doors, upon completion of which operation the automatic switch device will be restored to original position so that current is again cut off from the motor and the switch device is set for the door opening operation such as first referred to above. Another object is to provide mechanical connections of a simple and efficient character between the motor and the doors for opening and closing the latter according to the direction of rotation of the motor, these connections being readily disconnectable so that if the device should fail to function properly, then the doors may be opened and closed manually.

The full objects and advantages of my invention will appear in connection with the detailed description thereof, and the novel features of my inventive idea will be particularly pointed out in the claims.

In the accompanying drawings which illustrate one form in which my invention may be embodied—

Fig. 1 is a top plan view of the device showing it connected for operating doors of a building. Fig. 2 is a side elevational view of the device. Fig. 3 is a side elevational

view on an enlarged scale of the motor and gearing driven thereby. Fig. 4 is a view in section on the line 4—4 of Fig. 3. Fig. 5 is a top plan view of a switch device. Fig. 6 is a view in section on the line 6—6 of Fig. 5. Fig. 7 is a wiring diagram showing the setting for opening doors. Fig. 8 is a wiring diagram showing the setting for closing doors.

Referring to the particular construction shown in the drawings, it will be seen that there are a number of supporting beams or cross members 10, 12, 14 and 16, which are located in the building at a height corresponding approximately to the upper end of the doors which are to be operated. The members 10 and 12 support depending guides 18 and 20 in which an elongated member shown as the tube 22 is slidably mounted. This tube at its upper side is provided with a rod 24 which extends between enlargements 26 and 28 on the ends of the tube 22. The rod 24 acts as a truss rod to prevent sagging of the tube. The rod 24 carries two collars 30 and 32 for a purpose which will appear later. The underside of the tube 22 is provided with rack teeth 34 which are engaged by the teeth of a pinion 36 secured to one end of a transverse shaft 38, the other end of which carries a worm gear 40 meshing with a worm 42 secured to the shaft 44 of an electric motor 46. The worm and worm gear obviously constitute a reduction gearing. The motor and a bracket 48 are secured to the underside of the supports 14 and 16. The bracket 48 carries the gearing just referred to and also carries an additional guide 50 for the slidable tube 22 as best shown in Fig. 4. In the embodiment shown in the drawings, the enlargement 28 carries a cross bar 52, the ends of which are connected by links 54 and 56 to the doors D of the garage or building. The links 54 and 56 have downturned ends which fit into holes in the cross bar 52 and in brackets 58 and 60 respectively, these brackets being secured to the upper portions of the doors. The links may be readily detached so that the doors may be operated manually if for any reason the device should fail to operate properly. It is

evident that when the rack is moved into its forward position as shown in Figs. 1 and 2, the doors will be opened and it will be understood that when the rack is moved rearward-
 5 ly, the doors will be closed. The beams 12 and 14 are connected by a short member 62 to which a bracket 64 is secured. This bracket carries a plate 66 of insulating material such as fiber. Secured to one side of the plate 66,
 10 there are three spring contact fingers 68, 70 and 72. The finger 70 is connected to a return wire 74 while the fingers 68 and 72 are both connected to a wire 76 extending to a contact post 78 adapted to be engaged by a
 15 movable switch member 80. The switch member 80 is also adapted to be engaged with a contact post 82 when moved from engagement with the post 78. The manually operable switch embodying the movable member
 20 80 may be placed in any convenient location as inside of a house or any other suitable place outside the garage having the doors which are to be controlled. The post 82 is connected by a wire 84 with a contact finger 86 carried by the plate 66. The motor 46 has a winding 88, one end of which is connected to a contact finger 90 and the other end of which is connected to a double contact finger 92. The motor 46 has a second winding 94, one
 25 end of which is connected to the return wire 74 and the other end of which is connected to a contact finger 96. The contact finger 96 is connected by a wire 98 with a contact finger 100 and is connected by a wire 102 with a contact finger 104. The post 90 is connected by a wire 106 with a contact finger 108. A contact finger 110 is connected by a wire 112 with the return wire 74, it being understood that all of these contact
 30 fingers are carried by the plate 66 and are arranged in the manner shown in Figs. 7 and 8. A switch arm 114 is pivotally mounted on a rod 116 carried by the bracket 64 as shown in Figs. 5 and 6. The arm 114 carries an insulating block 118 in which four contact plates 120, 122, 124, and 126 are set. Assuming that the doors are closed and it is desired to bring them into the open position shown in Fig. 1, the switch member 80 is moved into
 35 the position shown in Fig. 7 so as to engage the post 78. The switch arm 114 at this time is in such position that the plate 120 bridges the fingers 72 and 100, the plate 122 bridges the fingers 70 and 92 while the plate 124 bridges the fingers 68 and 108. Current will now flow from the feed wire 128 in the direction indicated by the arrows through the wire 76, plate 120, wire 98 and motor winding 94 to the return wire 74. Current will also flow
 40 from the wire 76 through the plate 124, wire 106, motor winding 88 and plate 122 to the return wire 74. The motor is thus turned in the proper direction to extend the rack 34 thereby causing the links 54 and 56 to force the doors into open position. As they reach
 45

this position, the collar 30 on the rod 24 engages a trip arm 130 which is pivoted on the rod 116. The arm 130 is connected to the switch arm 114 by a coiled spring 132 so that as soon as the arm 130 has passed dead center, the spring 132 moves the arm 114 into the position shown in Figs. 5 and 8 with a quick snappy action. Current to the motor is by this action cut off since it cannot now flow through the wire 76. Therefore, the doors will remain in open position until the movable switch member 80 is moved into the position shown in Fig. 8 in contact with the post 82. Current will now flow through the wire 84 and plate 120 to the finger 96 where the current divides, one part going through the motor winding 94 to the return wire 74 and the other part going through the wire 102, plate 122, motor winding 88, plate 126 and wire 112 to the return wire 74. The motor is thus again rotated but in the reverse direction from that previously referred to so that the rack 34 is retracted to close the doors. Just as they are reaching their closed position, the collar 32 on the rod 24 engages the trip arm 130 and throws the switch arm back into the position shown in Fig. 7. The motor is now stopped since no current can flow through the wire 84. The doors will remain in closed position until the movable switch member 80 is moved manually into the position shown in Fig. 7 whereupon the door opening operation will be repeated since the contact plates 120, 122, and 124 have already been automatically placed in proper position for this operation.

I claim:

1. A door operating device comprising an overhead support, rounded guides extending downwardly from said support, an elongated cylindrical member slidably mounted in said guides, rack teeth carried by the underside of said member, a pinion meshing with said teeth, a motor adapted to drive said pinion in opposite directions for reciprocating said cylindrical member, and connections between said cylindrical member and the doors for opening and closing the latter.

2. A door operating device comprising an overhead support, rounded guides extending downwardly from said support having openings in their lower sides, an elongated cylindrical member slidably mounted in said guides, rack teeth extending down from the lower side of said cylindrical member through said openings, a pinion meshing with said teeth, a motor adapted to drive said pinion in opposite directions for reciprocating said cylindrical member, and connections between said cylindrical member and the doors for opening and closing the latter.

3. A door operating device comprising an overhead support, rounded guides extending downwardly from said support, a tube

slidably mounted in said guides, a truss rod above the upper side of said tube connecting the ends thereof, rack teeth carried by the underside of said tube, a pinion meshing with said teeth, a motor adapted to drive said pinion in opposite directions for reciprocating said tube, and connections between said tube and the doors for opening and closing the latter.

10 4. A door operating device comprising an overhead support, rounded guides extending downwardly from said support, a tube slidably mounted in said guides, a truss rod above the upper side of said tube connecting the ends thereof, rack teeth carried by the underside of said tube, a pinion meshing with said teeth, a motor adapted to drive said pinion, a switch for reversing the direction of rotation of said motor, two spaced enlargements carried by said rod for alternately throwing said switch reversely, and connections between said tube and the doors for opening and closing the latter.

25 5. A door operating device comprising an overhead support, rounded guides extending downwardly from said support, a tube slidably mounted in said guides, a truss rod above the upper side of said tube connecting the ends thereof, rack teeth carried by the underside of said tube, a pinion meshing with said teeth, a motor adapted to drive said pinion, a switch for reversing the direction of rotation of said motor, a trip arm, a stressing device cooperating with said trip arm and said switch, said stressing device causing said switch to move from one position to the other when said trip arm passes over dead center, two spaced enlargements carried by said truss rod for alternately engaging opposite sides of said trip arm, and connections between said tube and the doors for opening and closing the latter.

40 In testimony whereof I hereunto affix my signature.
